GAS BURNER

Edward J. Haedike, Chicago, Ill., assignor to
 National Machine Works, Chicago, Ill., a corporation of Illinois

Application December 7, 1938, Serial No. 244,371

17 Claims. (Cl. 158—109)

The present invention relates to improvements in forced draft gas burners adapted for industrial and domestic use.

One of the objects of the present invention is to provide a novel fuel gas burner which has a substantially cylindrical discharge end adapted to be inserted into a combustion chamber and which is interchangeable with various standard types of oil burners, particularly in conversion installations.

Another object of the invention is to provide a new and improved fuel gas burner having an annular flame in close contact with a concentric stream of secondary air under low pressure.

A further object is to provide a novel fuel gas burner of the foregoing character which is simple, compact and inexpensive in construction and which is quiet, efficient and economical in operation.

Still another object is to provide a new and improved fuel gas burner which is readily and conveniently adjustable from the exterior of the furnace and without disturbing the burner installation to vary the capacity of the burner, to vary the fuel-air ratio and the ratio of primary air to secondary air, and to adapt the burner for the use of different types of fuel gas, such, for example, as manufactured gas, natural gas or a mixture of the two.

A further object is to provide a gas burner of the foregoing character embodying a novel pilot burner.

Other objects and advantages will become apparent as the description proceeds.

In the accompanying drawings,

Figure 1 is a fragmentary longitudinal vertical sectional view of a gas burner embodying the features of the invention.

Fig. 2 is a fragmentary plan view.

Fig. 3 is a fragmentary vertical sectional view taken partially along the line 3—3 of Fig. 1.

Fig. 4 is a right end elevational view.

Referring more particularly to the drawings, the burner constituting the exemplary embodiment of the invention comprises a burner housing which is preferably in the form of an elongated metal tube 1. One end of the burner tube 1 is supported by and opens to a casing 2 which defines a wind box or low pressure air chamber 3 adapted to supply all of the air, both primary and secondary, for complete combustion. It will be understood that the other end of the burner tube 1 is adapted to be mounted within a well or opening (not shown) in one wall of a furnace combustion chamber (not shown).

The casing 2 may be of any suitable form, and as herein shown is cylindrical in shape, with one end telescopically receiving the outer end of the burner tube 1, and the other end formed with an access opening 4 closed by a removable cover plate 5. Two parallel vertical rods 6 extend adjustably through two apertured lugs 7 on opposite sides of the casing 2, and are adapted to be secured therein by means of set screws 8. The rods 6 constitute supporting legs adapted to rest on a suitable foundation, such as a floor (not shown).

Air for combustion is supplied at a low pressure to the chamber 3 from a blower 9. In the present instance, the blower 9 has a peripheral housing 10 which is rigidly mounted directly on the casing 2, and preferably is integral therewith. The blower housing 10 has an axial atmospheric air inlet 11 in one side, and a tangential air outlet 12 opening through the top wall of the casing 2 to the chamber 3. A plate 13 integral with a horizontal bracket 13^a is bolted to and closes the other side of the blower housing 10. Mounted on the bracket 13^a is an electric drive motor 14 having a shaft 15.

The motor shaft 15 projects centrally through an opening 16 in the plate 13 into the blower housing 10, and supports a rotor 17 having a closed inner end disk 18, an annular outer end disk 19 in alignment with the air inlet 11, and a plurality of peripherally spaced radial vanes 20 between and interconnected with the disks. A suitable damper 21 is adjustably mounted in operative association with the air inlet 11 to control the amount of air supplied to the chamber 3 and hence the air pressure therein.

Mounted within and extending along the bottom of the burner tube 1 is a mixing tube 22 having an inlet cone 23 and an expanding outlet cone 24. The inlet cone 23 is closed by an end wall 25 and is provided in the top adjacent the wall with an air inlet opening 26 in communication with the air chamber 3. A shutter plate 27 is pivotally bolted to the mixing tube 22 for angular adjustment into different degrees of registration with the inlet opening 26 to control the supply of primary air. Removably threaded through the end wall 25 to extend axially into the inlet cone 23 is a gas or fuel nozzle 28. An orifice body 29 having an axial discharge orifice 30 of selected size is removably secured in the discharge end of the nozzle 28. Different sized orifices may be employed for different types of fuel gas, and to vary the rate of input and capacity of the burner. Secured to the inlet end of the nozzle 28 is a T pipe fitting 31 closed at the

outer end by a removable screw plug 32 and connected at the side to a gas supply pipe 33. The pipe 33 extends through an opening 33^a in one side of the casing 2 for connection to a suitable source (not shown) of fuel gas under pressure, and is secured in position by a set screw 33^b to support the outer end of the mixer assembly. It will be noted that removal of the cover plate 5 affords access to the shutter 27 and the plug 32, and that removal of the latter affords access to the orifice body 29, so that the ratio of fuel to air and the ratio of primary air to secondary air may be quickly and conveniently adjusted.

The discharge end of the mixing tube 22 is rigid, and preferably formed integral, with a burner head 34 which is arcuate in shape and formed with an arcuate fuel-air mixture discharge port 35 opening from the expanding cone 24. The terminal portion of the head 34 is closely encircled by the burner tube 1 which serves to support the discharge end of the mixer assembly. In the present instance, the periphery of the head 34 is formed with a plurality of lugs 36 which engage the interior of the tube 1 and which cause the portions of the head between the lugs to be slightly separated from the tube by a space 37. The burner head 34 extends peripherally through a substantial portion of the circumference of the burner tube 1, with the terminal side margins 38 spaced to define a central recess 39 open at the top. A flanged pilot tip plate 40 in the form of an outwardly opening cup is rigidly secured in position, as by welding, between the spaced side margins 38 of the burner head 34, and projects downwardly into the recess 39. The upper flange portion of the plate 40 extends concentrically within the burner tube 1 so as to complete the full circular form of the burner head assembly. The lower flange portion of the plate 40 extends in concentrically spaced relation to the inner surface of the burner head 34 to define an intermediate arcuate or partially annular secondary air discharge port 41 in communication with the pressure chamber 3.

In operation, fuel gas under pressure discharges through the orifice 30 at a high velocity, and induces the flow of a proportionate amount of primary air under a low pressure from the chamber 3 through the opening 26 into the tube 22. The pressure of the air is controllable by means of the damper 21. The fuel and primary air are thoroughly mixed in the tube 22, and the resultant mixture issues under pressure from the arcuate fuel port 35 for combustion in the furnace chamber. Secondary air under pressure issues from the arcuate port 41 in a stream defining a closely spaced hollow internal air core. As a result, the fuel and air are intimately mixed to insure efficient and complete combustion. The mixture burns quietly and with a soft long annular flame.

A pilot burner is provided to ignite the fuel mixture. In the present instance, the pilot burner comprises a block 42 of refractory material mounted within the flanged trip plate 40 and formed with a central burner tunnel or well 43 slightly offset upwardly from the axis of the main burner head 34. A pilot burner tube 44 is mounted in an opening 45 in the base of the plate 40, and is formed with a main passage 46 communicating longitudinally with the tunnel 43 and adapted to supply a stream of a pilot fuel-air mixture. Mounted in the outer end of the passage 46 is a disk 47 formed with a plurality of burner ports 48. One port 48 opens

5 axially through the disk 47, and the other ports are annularly spaced, with the lowermost ports inclined to discharge downwardly. The inclined ports serve to keep the flame from blowing off the pilot tip, i. e., retards the pilot flame.

To support the burner tube 44 in position and for connection to a suitable source of fuel, a pilot mounting plate 50 is supported within an opening 51 in the top of the main burner tube 1 by an adapter bracket or plate 52. This bracket 52 has a base flange 53 arcuate in shape to conform to the curvature of the tube 1, and circumscribing the opening 51. One end portion of the bracket 52 is formed with an inclined hood or top wall 54 which is integral with and rises from the flange 53 and which serves to close the end of the opening 51 adjacent the burner tube 44. The remaining portion of the bracket 52 is formed with an upstanding marginal wall 55 about the opening 51 and integral with and circumscribed by a horizontal top flange 56. The mounting plate 50 is provided with an external marginal flange 57 resting on and secured to the flange 56, and the central portion thereof projects downwardly through the opening 51 and defines an upwardly opening well or recess 58. One end of the mounting plate 50 is formed with a wall 59 normal to and abutting the free edge of the hood 54. A fitting 60 integral with the base wall of the recess 58 is formed with a discharge bore 61 opening through the wall 59 and adapted to be connected through one of two tapped lateral openings 62 to a tube 63 leading to a source of fuel gas (not shown). A lighter is mounted in the other opening 62.

40 The passage 61 in the plate 50 is connected to the burner passage 46 through a proportional fuel and air mixer. This mixer preferably comprises a Venturi tube 64 threaded at the discharge end into the burner tube 44 and having a plurality of peripherally spaced apertures 65 opening from the chamber 3 to the inlet end. A tubular nozzle 66 with a discharge orifice 67 is threaded at one end into the inlet end of the mixing tube 64 and at the other end into the passage 61.

45 In operation, fuel gas under pressure issues from the orifice 67 at a high velocity, and induces the flow of a proportionate amount of air under a low pressure from the chamber 3 through the apertures 65 into the tube 64. The fuel and air are thoroughly mixed in the tube 64, and the resultant mixture passes through the burner ports 48 for combustion to provide a pilot flame. The refractory block 42 protects the pilot burner 50 44 from becoming overheated by reflected or radiant heat from the combustion chamber, and also serves to promote combustion.

55 Automatic means may be employed for controlling the supply of fuel gas to the main burner. This control means includes a fuel bleed line or conduit 68 which is opened and closed respectively to institute and cut off the main supply of fuel. The conduit 68 is connected to a passage 69 in the wall of the pilot burner tube 44 discharging to the burner well 43 so that the bleeding gas will pass into the combustion chamber and enlarge the pilot flame. Other primary details of the control means form no part of the present invention, and hence are not disclosed.

60 A safety valve 70 is provided to automatically close the conduit 68 and thereby effect a cut-off of the main fuel supply in the event that the pilot flame is extinguished. The valve 70 is interposed in the conduit 68, and is mounted in the

recess 58 of the plate 50, the portion of the conduit from the valve to the passage 69 extending through an opening 71 in the wall 59. The valve 10 may be of any suitable standard type adapted to close automatically in response to the temperature drop resulting when the flame is extinguished, and hence is not disclosed in detail. It is sufficient to state that the valve 10 is controlled by a suitable thermocouple 72 to which it is connected by a control lead 73 extending through an opening 74 in the wall 59. The hot junction of the thermocouple 72 projects through a lug 75 on the burner tube 44 into the burner well 43 and is inclined downwardly into the path of the pilot flame.

The novel fuel gas burner herein disclosed has a long soft annular flame in direct contact internally with a conforming stream of secondary air. As a result, combustion is quiet, complete and efficient, only a small amount of excess air being present.

It will be evident that the burner is readily and conveniently adjustable for operation under widely different conditions. Thus, the burner may be adjusted to vary the capacity, to vary the ratio of fuel and air in the primary mixture and the ratio of primary and secondary air, and to adapt the burner for different types of fuel gas such, for example, as manufactured gas, natural gas or a mixture of the two. Most of the burner structure is located externally of the furnace, and consequently the foregoing adjustments can be made without disturbing the installation.

The fuel burner is simple, compact and inexpensive in construction and it is especially adapted for use as a conversion burner in domestic installations. The burner head is round and interchangeable with various types of fuel oil burners.

A novel and advantageous pilot burner is also provided. The pilot burner receives a controlled proportionate mixture of fuel and air and discharges into the annulus of the main burner flame. The tip of the pilot burner is protected from becoming overheated by refractory material which also serves to promote combustion. The pilot burner is also removable for inspection without disturbing the installation of the main burner. All of the air for combustion, not only for the main burner but also for the pilot burner, is received from a common low pressure source.

I claim as my invention:

1. In a fuel gas burner, in combination, a cylindrical burner head having arcuate port means formed and arranged to discharge a coaxial arcuate stream of a fuel-air mixture under pressure, and having concentric arcuate port means formed and arranged to discharge a coaxial arcuate stream of secondary air inside of and closely contiguous to said first mentioned stream, and a pilot burner arranged to discharge a pilot stream of fuel centrally of said last mentioned port means into the hollow core zone of said two first mentioned streams.

2. In a gas fuel burner, in combination, a casing constituting an air chamber and having a tubular discharge end, means for supplying air under pressure to said casing, a fuel and air mixer in said casing and having a primary air inlet opening from said casing and a fuel supply orifice nozzle and having an expanding discharge cone, means for supplying gaseous fuel to said nozzle, and a circular burner head integral with the end of said discharge cone and periph-

erally embraced and supported by said tubular discharge end, said head being shaped to define concentric arcuate discharge ports in communication respectively with said chamber and said discharge cone.

3. In a gas fuel burner, in combination, a casing constituting an air chamber and having a tubular discharge end, means for supplying air under pressure to said casing, a fuel-air mixing tube in said casing and having a primary air inlet opening from said casing and a fuel supply orifice nozzle, means for directing gaseous fuel under pressure to said nozzle, and a burner head connected with said mixing tube, said head defining concentric discharge ports in a plane transverse to the axis of said mixing tube and in communication respectively with said chamber and said mixing tube and extending arcuately through the major portion but less than the entire portion of the circumference of said discharge end, said port which communicates with said mixing tube having the center of its arcuate configuration displaced laterally of the axis of the mixing tube toward the side in which a gap occurs between the ends of the arcuate port.

4. In a fuel gas burner, in combination, an annular burner head formed with a notch in the top and defining an arcuate fuel-air mixture discharge port extending from one side of said notch to the other, means for supplying a fuel-air mixture to said port, a pilot plate rigidly secured in said notch and completing the circular form of said head, said plate projecting into the center space of said head and coacting with said head to define an arcuate air discharge port concentric with said first mentioned port, means for supplying air to said last mentioned port, and a pilot burner mounted to discharge through said plate.

5. In a fuel gas burner, in combination, an arcuate burner head member defining an arcuate fuel-air mixture discharge port, means for supplying a fuel-air mixture to said port, a pilot plate rigidly secured to said member between the ends of said port and coacting with said head to define an arcuate air discharge port concentric with said first mentioned port, means for supplying air to said last mentioned port, and a pilot burner mounted to discharge through said plate.

6. In a fuel gas burner, in combination, a burner head defining an arcuate fuel-air mixture discharge port, means for supplying a fuel-air mixture to said port, a cup-shaped pilot plate within said head and coacting therewith to define an arcuate air discharge port concentric with said first mentioned port, means for supplying air to said last mentioned port, a refractory block mounted in said plate and formed with a tunnel, a pilot gas burner having a plurality of fuel discharge ports mounted to discharge into said tunnel, certain of said last mentioned ports being inclined to direct the issuing fuel toward the side wall of said tunnel, and means for supplying a fuel-air mixture to said pilot burner.

7. In a fuel gas burner, in combination, a burner tube having a circular discharge end, a closed casing connected to the other end of said tube and coacting therewith to define a low pressure air chamber, a blower rigid with said casing and discharging thereto, said blower having an adjustable air inlet, a fuel and air mixing tube extending through said burner tube and into said casing, an orifice fuel nozzle mounted in

the inlet end of said mixing tube and having a fuel supply line extending from said casing, the inlet end of said mixing tube having an air inlet opening from said chamber and controlled by an adjustable damper to vary the ratio of primary air to secondary air, an arcuate burner head on the discharge end of said mixing tube closely encircled by the discharge end of said burner tube and defining an arcuate fuel-air mixture port communicating with said mixing tube, a pilot tip plate rigidly mounted in the burner head and coacting with the inner arcuate surface thereof to define an arcuate secondary air port in communication with said chamber and concentric with said mixture port, and a pilot burner mounted on said burner tube and discharging through said tip plate substantially centrally of said ports.

8. In a fuel gas burner, in combination, a burner tube having a circular discharge end, a closed casing connected to the other end of said tube and coacting therewith to define a low pressure air chamber, a blower rigid with said casing and discharging thereto, said blower having an adjustable air control damper, a fuel and air mixing tube extending through said burner tube and into said casing, an orifice fuel nozzle mounted in the inlet end of said tube and having a fuel supply line extending from said casing, the inlet end of said mixing tube having an air inlet opening from said chamber and controlled by an adjustable damper to vary the ratio of primary air to secondary air, an arcuate burner head on the discharge end of said mixing tube closely encircled by the discharge end of said burner tube and defining an arcuate fuel-air mixture port communicating with said mixing tube, and means coacting with the inner arcuate surface of said head to define an arcuate secondary air port in communication with said chamber and concentric with said mixture port.

9. In a fuel gas burner, a casing defining a low pressure air chamber, means for supplying air under pressure to said chamber, a burner head having fuel-air mixture discharge port means and having air discharge port means opening from said chamber, a fuel and air mixer having an adjustable air inlet opening from said chamber and fuel inlet means and discharging to said first mentioned port means, a pilot burner, and a fuel-air mixer connected to said pilot burner and having an air inlet opening from said chamber and fuel inlet means.

10. In a fuel gas burner, in combination, an elongated burner housing having an opening in one side wall and defining an air pressure chamber, an adapter plate secured to said wall about said opening, a mounting plate inset in said adapter plate, a main burner unit mounted in one end of said housing and receiving air from said chamber, and a pilot burner supported from said mounting plate within said housing and discharging from said housing adjacent said main burner unit.

11. In a fuel gas burner, in combination, a burner head defining an arcuate fuel-air mixture discharge port, means for supplying a fuel-air mixture to said port, a cup-shaped pilot plate within said head and coacting therewith to define an arcuate air discharge port concentric with said first mentioned port, means for supplying air to said last mentioned port, a refractory block mounted in said plate and formed with a tunnel, a pilot gas burner mounted to discharge into said tunnel, and means for sup-

plying a fuel-air mixture to said pilot burner.

12. In a fuel gas burner, in combination, a burner head having a fuel-air mixture discharge port and a contiguous secondary air port, means for supplying a fuel-air mixture to said discharge port, means for supplying air to said air port, a refractory block mounted in said head contiguous to said ports and formed with a tunnel displaced laterally from said ports and out 10 of the direct path of fuel and air issuing therefrom, a pilot gas burner having a plurality of fuel discharge ports mounted to discharge into said tunnel, certain of said last mentioned ports being inclined to direct the issuing fuel toward 15 the side wall of said tunnel, and means for supplying fuel to said pilot burner.

13. In a gas fuel burner, in combination, an elongated casing constituting an air pressure chamber and having a discharge end, means for 20 supplying air under superatmospheric pressure to said casing, a burner head in the discharge end of said casing and having fuel discharge passages and secondary air discharge passage means in contiguous relationship, said passage 25 means being open to said casing to receive air therefrom, a plurality of independent fuel and air proportioning mixers mounted within said casing to discharge fuel mixtures to different ones of said fuel passages, each fuel mixer including a mixing tube having a primary air inlet opening directly from the interior of said casing to receive air by induction therefrom and including a fuel jet orifice to discharge fuel under pressure into said tube, and means for adjustably proportioning the ratio of primary to secondary air for the fuel discharged from at least one of said mixers independently of the other mixer or mixers.

14. In a gas burner, in combination, a casing 40 constituting an air chamber and having a tubular discharge end, means for supplying air under pressure to said casing, a fuel and air mixer in said casing, said mixer including an elongated mixing tube with an inlet cone opening to the interior of said casing and an expanding discharge cone and extending longitudinally of said casing, and including a fuel supply orifice nozzle discharging axially into said inlet cone, means for supplying gaseous fuel under pressure to said 45 nozzle, the discharge end of said expanding cone merging smoothly from a conical form into an arcuate form of substantially greater diameter to constitute a burner head with an arcuate discharge port extending through the major portion 50 of the circumference of said casing and with the axis of said head paralleling that of said expanding cone, and means located within the curve of said head for directing air from said casing for secondary combustion.

15. In a gas fuel burner, in combination, a casing constituting an air chamber and having a tubular discharge end, means for supplying air under pressure to said casing, a fuel and air mixing tube mounted in and extending longitudinally and eccentrically of said casing, said mixing tube having an air inlet open to said casing and having a discharge end with an arcuate outlet port and closely circumscribed by said tubular discharge end of said casing, means for supplying fuel under pressure into the inlet of said tube whereby to induce the flow of primary air from said casing into said inlet and to produce a fuel mixture to issue from said port, and means in said tubular discharge end of said cas-

ing for causing discharge of secondary air from said casing contiguous to said port.

16. In a fuel gas burner, in combination, an elongated burner housing having an opening in one side wall and defining an air pressure chamber, a mounting plate supported in and closing said opening and projecting into said housing, a main burner unit mounted in one end of said housing and receiving air from said chamber, and a pilot burner supported from said mounting plate within said housing and discharging from said housing adjacent said main burner unit.

17. In a gas fuel burner, in combination, a casing constituting an air chamber and having a tubular discharge projection thereon with an open end, means for supplying air under pressure to said casing, a fuel and air mixer in said casing, said mixer including an elongated mixing tube with an inlet cone opening to the interior of said casing and an expanding discharge cone, said discharge cone being arranged to project longitudinally through said casing extension but eccentrically located with respect to the longitudinal axis of the latter, said mixer also includ-

ing a fuel supply orifice nozzle discharging axially into said inlet cone, means for supplying gaseous fuel under pressure to said nozzle, the outer end of said discharge cone flaring smoothly outward into an enlarged integral head portion having an arcuate exterior contour conforming to the curvature of the encircling end portion of said casing and snugly fitted therein, said head portion of the discharge cone having a deep indentation in one side thereof and in which the indented wall is dished down to coact with the opposite wall of the head to define an arcuate end portion at the outer end of said head for the emission of fuel and primary air, and means substantially filling the space left in the end of said casing extension by said indentation but spaced sufficiently from said head portion to define with it an arcuate secondary air emission port running along the inner perimeter of the first mentioned port and communicating with the interior of said casing for directing air from the casing for secondary combustion.

EDWARD J. HAEDIKE.
